NOODLE CUTTING MACHINE

Anthony P. Giunta, 1035 Christian St., Philadelphia, Pa.

Filed Feb. 9, 1960, Ser. No. 59,326

Term of patent 14 years

(Cl. D55—1)

FIG.1.

FIG.2.

FIG.3.

FIGURE 1 is a perspective view of a noodle making machine showing my new design;

FIGURE 2 is a plan view, on a large scale, of the noodle cutting element thereof; and

FIGURE 3 is a bottom view of the noodle cutting element, on the same scale as FIG. 2.

I claim:

The ornamental design for a noodle cutting machine, substantially as shown.
